UNITED STATES PATENT OFFICE

CORNELIUS G. ELY, OF CHICAGO, ILLINOIS, ASSIGNOR TO GRIGSBY-GRUNOW COMPANY,
OF CHICAGO, ILLINOIS, A CORPORATION OF ILLINOIS

DESIGN FOR AN ESCUTCHEON PLATE FOR RADIO RECEIVERS

Application filed February 28, 1931. Serial No. 38,860. Term of patent 7 years.

To all whom it may concern:

Be it known that CORNELIUS G. ELY, a citizen of the United States of America, residing at 344 North Lockwood Avenue, Chicago, Illinois, in the county of Cook and State of Illinois, has invented a new, original, and ornamental Design for Escutcheon Plate for Radioreceivers, of which the following is a specification, reference being had to the accompanying drawing, forming part thereof.

The figure is a perspective view of an escutcheon plate for radio receivers, showing my new design.

The escutcheon plate is substantially thin and flat.

I claim:

The ornamental design for an escutcheon plate for radio receivers as shown and described.

CORNELIUS G. ELY.
